UNITED STATES PATENT OFFICE.

GEORGE W. DONNING, OF STAMFORD, CONNECTICUT, ASSIGNOR TO
HARRY T. AMBROSE, OF ORANGE, NEW JERSEY.

TYPE-WRITER.

No. 826,488.

Specification of Letters Patent.

Patented July 17, 1906.

Application filed September 15, 1894. Serial No. 224,628.

To all whom it may concern:

Be it known that I, GEORGE W. DONNING, a citizen of the United States, residing at Stamford, in the county of Fairfield and State 5 of Connecticut, have invented certain new and useful Improvements in Type-Writers; and I do hereby declare the following to be a full, clear, and exact description of the invention, such as will enable others skilled in the art to which it appertains to make and use the same.

This invention relates to type-writers, and particularly to a combination work-holder and multicarbon carrying and holding device.

The object of my invention is to provide simple, effective, and easily-operated devices for facilitating and perfecting the operation of and greatly expediting the work of the operator, in connection with devices for holding and lifting or separating a plurality of carbon-sheets from a flat platen or from the work-sheets sustained thereby and for clamping the work-sheet to said platen; these various parts for holding, separating, and clamping the work being operatively connected and having operating mechanism by means of which they may be simultaneously raised for permitting arrangement of the work or lowered and held down while the impression is being made, all of which operations are effected without necessity of the operator employing her hands for operating such parts.

A further object is to provide a simple and effective device for carrying a plurality of carbon sheets or rolls in connection with one or more work-holders operable simultaneously or successively in a single operation and by a single device.

A further object is to provide means for separating each of the plurality of carbon-sheets from the work and elevating the same and the work-holders to predetermined relatively different heights to permit a rapid removal and insertion of the work-sheets.

A further object is to provide means for properly locating or positioning or registering the work on the platen.

A further object is to provide means for holding or confining or retaining the free end of the work-sheet.

A further object is to provide means for effecting the proper return of the various op-

erable parts to their respective normal positions and at the same time to cause the work-holder to engage and press upon the work-sheet.

A further object of my invention is to provide devices for holding the edges of a plurality of carbon-sheets, for clamping and holding a work-sheet or work-sheets on the platen, and for simultaneously raising said devices and at the same time effecting separation of the respective carbon-sheets through the medium of a foot-treadle, a connecting-rod, a crank-lever, and other connections for permitting the work, such as a statement-blank or billing-form or the like, to be conveniently removed from or applied to the platen in proper relation to the carbon-sheets without the necessity of handling any of said carbon-sheets, whereby the handling of the work is expedited and soiling of the fingers and the paper is avoided, with the attending and resulting advantages of the elimination of the objections thereto.

Another object of my invention is to provide for the winding up and removing of the respective carbon-sheets from the face of the platen, so that the latter may, if desired, be used temporarily for other work.

Another object of the invention is the provision for the convenient insertion or removal of the work or paper sheet without the necessity and the attending disadvantage of pushing the writing mechanism back to the rear of the track-frame.

Another object is to provide for moving vertically a tape work-holder simultaneously with the raising of the carbon-sheets away from the platen, with means for keeping the tape work-holder taut when it is so raised from the printing-surface.

Another object is to provide for the positioning and movement of each of the plurality of carbon-sheets, which may be manifolding paper or ribbons carbonized or otherwise provided with a transferring medium of the same color or a plurality of colors arranged in columns or in paths.

Another object is to provide automatic means for effecting operation of the plurality of carbon-holding and work-clamping members.

With these objects in view I preferably arrange the plurality of carbon-sheets on a per-

manent fixture, such as a roll or a plurality of rolls mounted on the track-frame on the platen or on the table, and in connection therewith provide devices for holding, for raising, and for separating the free edges of the respective carbon-sheets for facilitating the rapid insertion and removal of the work sheet or sheets upon which the impression is made. As it is desirable that the work-sheet placed beneath the upper sheet of carbon, as well as the work-sheet placed thereon, shall be firmly held to the platen while being written upon, I provide, in connection with said carbon holding, raising, and separating device, 15 a work-holder clamp or clamps operable by or independent of said device.

The invention resides also in various novel constructions and arrangement and combination of parts, as will be hereinafter more 20 fully described and claimed.

In the accompanying drawings, forming a part of this specification, I have illustrated one of many embodiments of my invention, it being understood that the same is susceptible of embodiment in various forms and yet be within the spirit of my invention.

In the drawings, Figure 1 is a view in side elevation of a flat-platen type-writer, the longitudinal tracks of which have been broken 30 away, showing the arrangement of the carbon-rolls, two carbon-holders, a work-confining clamp, and the foot lever or treadle for effecting the raising of said carbon-holder and the work-confining clamp simultaneously. Fig. 2 is a view in plan thereof with the movable carriage omitted. Fig. 3 is a view similar to Fig. 1, with the movable carriage and the tracks therefor omitted, showing the carbon-holders and the work-confining 35 clamp in the positions which they assume, respectively, when the foot-lever is operated. Fig. 4 is a view in front elevation, showing the position of the parts when elevated as shown in Fig. 3. Fig. 4^a is a transverse section through the work-confining clamp and the carbon-holder levers, showing the relation of these parts to each other and to the edge of the platen. Fig. 5 is a view in detail of the upper carbon-holder and lifting device. 40 Fig. 6 is a similar view of the lower carbon-holder and lifting device. Fig. 7 is a transverse sectional view of the latter device, taken on the line 6 6, Fig. 6. Figs. 8 and 9 are views in detail in front and end elevation of 45 the work-confining clamp arranged at one side of the platen and operated simultaneously with the carbon holding and separating devices. Fig. 10 is a view in detail of a connecting-piece for effecting coöperation of the 50 two carbon holding and separating devices and the work-confining clamp. Fig. 11 is a view in detail of the device for effecting return of the operable parts to normal position. Figs. 12 and 13 are respectively views in 55 side elevation and in plan of a modified form

of the structure as organized for effecting automatic raising of the carbon-holders and work-holder.

Referring to the drawings, A designates a longitudinally-traveling carriage supported 70 on a track-frame B, which is disposed independent of or in position to rest upon a flat platen C.

D designates a transversely-movable carriage disposed on the longitudinally-movable 75 carriage A, already referred to.

The track-frame and the platen are preferably supported on a table E, provided with supporting legs or standards e, connected by a brace e² at their lower portions and by a 80 second brace e² at their upper portion. The rear end of the track-frame B is provided with a stop or abutment B³ to limit the backward travel of the carriage A.

Arranged, preferably, to the rear of the 85 platen C and on the table E toward its rear edge are brackets F F², preferably secured to the table in any preferred manner, as by the screws f f². Rotatably supported on the brackets F F² are rolls G and H, respectively, 90 which are designed to carry the carbon-paper in long continuous lengths, preferably, and to be drawn therefrom and positioned over the platen and held at the front by devices hereinafter more fully to be described. It is 95 to be understood that while I have only shown two rolls of carbon a greater or less number may be employed without changing my invention. The roller G is mounted on a shaft g, which rotates in bearings g² g³ and 100 carries adjustable sleeves g⁴. From this roll G is preferably unwound the upper carbon-sheet G². The carbon may have transverse or longitudinal strips of coloring different from the body or main portion of the carbon-sheet, as shown in Fig. 13. The roll H is similarly arranged on a shaft h, rotatably supported in bearings h² h³ and carrying adjustable sleeves h⁴. This roll H carries a lower carbon-sheet H². The particular construction and arrangement of these carbon-rolls G and H constitute the subject-matter 105 of another of my pending applications, filed February 14, 1903, Serial No. 143,421, and will not, therefore, be claimed specifically 110 herein. Also supported by a shaft i on the brackets F F² is a tape-tensioning roll I for holding the rear end of a work-confining tape I², more particularly described and claimed in my pending application filed February 10, 115 1903, Serial No. 142,788. The tape I² is secured at its forward end to a tape-holder I³, which is more particularly described and claimed in my pending application filed February 6, 1904, Serial No. 192,403, and like the 120 tape-holder I is transversely movable over the platen C.

The carbon-sheet G² is engaged at its forward end by a carbon-clamp holder J, which may be of any appropriate construction; but 130

in this instance I have shown the same as comprising two superposed members j^1 , pivoted together at one end at j^2 , so that the member j^1 may be swung outward from the member j^2 to permit insertion of the end of the carbon, it being understood that the two members when in normal holding position are close together. Projecting upward from the outer end of the member j^2 is a stud j^4 , which is received in the slotted end of member j^1 . The said carbon-holder J is preferably arranged on or secured to a bracket or standard j^5 , and this is mounted, as by screws j^6 , to an arm or lever J^2 , Fig. 5, which is provided at a point somewhat in advance of its rear end with a perforation j^7 , through which passes a spindle L , which is mounted transversely beneath the platen in brackets $l^1 l^2$ and is provided with a spiral spring l , engaging at one end with a collar l^5 , keyed to the spindle, and having its other end bearing against the under face of the platen C , as shown in Figs. 2 and 11. It is to be understood that spindle L fits tightly within the perforation j^7 , so that the lever J^2 is rendered rigid with the spindle.

Beyond the perforation j^7 in the lever J^2 is another perforation j^8 , which is penetrated by a screw or bolt m to connect said lever with a connecting-link M , pivoted at its lower end at n^2 to a foot-treadle M^2 , the treadle being pivoted at e^2 on the connecting-brace e^1 of the table-legs. It is to be understood, of course, that when the foot-treadle M^2 is operated, as shown in full lines in Fig. 3, and by reason of the position of the fulcrum j^7 of the lever J^2 the forward end of this lever J^2 will be elevated and carry with it the carbon-holder J , and thus raise the forward end of the carbon-sheet G , as shown in Fig. 3. It is to be understood that the spindle L is spring-actuated and operates in a direction opposite to the pull of the lever for returning said lever J^2 to normal position, as shown in dotted lines in Fig. 3.

To guide the movement of the lever J^2 , I provide thereon a boss or projection J^3 , designed to bear against the side of the platen and guide the lever J^2 in its upward movement and also prevent binding during such operation.

The carbon-sheet H^2 is engaged at its forward end by a carbon-clamp holder N , which is preferably of construction similar to the carbon-holder J , already described, comprising the two members $n^{11} n^{12}$, pivoted together at n^2 . The said carbon-holder N is preferably arranged on or secured to a bracket n , and this is mounted, as by screws n^3 , on a lever N^2 , preferably formed with upper and lower strengthening-flanges $n^5 n^6$ on its outer face, Figs. 6 and 7. The lever N^2 is preferably arranged in juxtaposition to the lever J^2 and is pivoted at its rear end loosely on the spindle L , already described, and to this

end is provided with a hub n^5 , which may carry an adjusting-screw n^6 , by means of which, if desired, as when but a single carbon is employed, the lever N^2 may be rigidly secured to spindle L . Intermediate of the length of the lever N^2 , and preferably some distance removed from its point of securement to the spring element L , is an elongated slot n^7 , and designed to work in this slot and also penetrate a perforation j^9 in the lever J^2 is a connecting-bolt O , having on one of its ends a nut o , the bolt normally occupying the lower portion of the slot, as shown in Fig. 1. When the foot-lever connecting with the lever J^2 is operated to elevate the forward end of said lever, said bolt O will ride in the slot n^7 until it reaches the upper portion thereof, when by the continued upward movement of the lever J^2 the lever N^2 will be caused to be raised at its forward end on its fulcrum to the position shown in full lines in Fig. 3. It will be observed that by the arrangement thus described and shown the lever J^2 will first be moved and have its forward end elevated and during the course of its upward movement cause the bolt O to move the lever N^2 , and thus the levers may be regarded as having both successive and simultaneous movement. By this means the levers are elevated to different relative heights away from the platen, and thus the carbon-sheets $G^2 H^2$ respectively, will be elevated to different heights relative to each other and to the platen, the carbon-sheet G^2 being above the carbon-sheet H^2 . The spring l , secured to the spindle L , tends to depress both of the levers J^2 and N^2 , and when pressure on the foot-lever is relieved the spring l will tend to return the said levers to normal position by reason of its action being in the direction opposite to the upward pull of the levers.

It will be understood that the elevation and raising of the carbon-sheets G^2 and H^2 to different heights relatively will effect the separation of the work-sheets, between which said carbon-sheets are interposed. The work-sheets may then be withdrawn without necessity of the operator touching the carbon-sheets, and then new work-sheets may be inserted, and upon release of the pressure on the foot-lever device the carbon-holder-operating levers will be actuated back to the platen by the spring-actuated spindle L , and the work-sheets will then be in position to be written upon. It will be observed that this entire operation has been effected without necessity of the operator utilizing her hands to operate the carbon-holders; but, on the contrary, the operator's hands have been free for the proper removal and insertion of the work-sheets, and not having to handle or touch the carbon-sheets and then the work-sheets it is manifest that there will be no smutting of said work-sheets by

the fingers of the operator. Besides, the handling of the work-sheets is thus greatly facilitated in removing and inserting them, permitting expeditious writing up of the said sheets and in a neat and cleanly manner.

It is to be understood that, if desired, I may employ in lieu of the foot-treadle a hand-lever properly disposed and connected with the carbon-holder-operating lever J^2 .

As a means for holding the work-sheet I may employ, in addition to the work-holding tape I^2 , a clamping member P , preferably disposed at the edge of the platen C and in juxtaposition to the carbon-holder-operating levers J^2 and N^2 and of the form preferably shown in Fig. 9, comprising a plate p , having its upper edge p^2 bent over, so that it may engage and hold the paper against the platen. This clamp P is preferably provided contiguous to its lower edge and by preference near its ends with inward-projecting studs or pins p^3 , which are designed to engage the lower face of the platen when the clamp is raised (in the manner presently to be described) and serve the dual function of limiting the extent of upward movement of the clamp and also for guiding such movement of the clamp—as, for instance, if the pin at one end strikes the lower face of the platen first it will hold the clamp at that end in a raised position until the pin at the opposite end engages the lower face of the platen, when the upper inturned edge of the clamp will, as is obvious, be properly arranged in a position above but level with the upper face of the platen. I may, if desired, elevate this clamp, so as to free it from engagement with the work-sheet and the upper face of the platen in any desired manner; but I elect to operate it simultaneously with and by the same mechanism employed to elevate the carbon-holders already described, and to this end provide the clamp P with a perforation p^4 , preferably half-way of the length of the clamp, and through this perforation the bolt O penetrates, as shown in Fig. 2, the same as it penetrates the lever J^2 . This clamp P is preferably extended back of the pivotal point of the levers J^2 and N^2 on the spindle L . To permit the raising of the clamp free of said spindle L , I provide the clamp with a cut-out or slot p^5 , so that the same will bridge the spindle. It is to be understood that by reason of the connection by the bolt O of the clamp P with the lever J^2 said clamp will be raised when the lever J^2 is operated and the pins p^3 will guide and limit the upward movement of said clamp in the manner already described. There is thus a coaction between the carbon-holder-operating levers and the said clamp, so that when the carbon-sheets are elevated away from the platen and effect a separation of the work-sheets the clamping device P is also raised away from the platen to release the same from engagement with

the paper sheets and permit withdrawal thereof. The said paper-clamp by reason of its extending downward parallel with the side edge of the platen and by reason of its being in close proximity preferably with said edge of the platen will serve as a work-gage, as well as a work-holder, so that there is therein constituted a combined work-holder and work-gage.

From the foregoing it will be observed that my invention includes a combined work-holder and work-gage operating in connection with and by the action of a carbon-holding device which is capable of being raised to a predetermined height relative to the platen for effecting a separation of the carbon from its contacting work-sheet, and auxiliary or second carbon-carrier constructed to operate simultaneously with the first-mentioned carbon-carrier in being raised away from the platen and effecting also a separation of the carbon from the work-sheet, together with means for effecting proper co-operation of said work-holder and carbon-holders and means for guiding and limiting the extent of movement of the operable parts to position the same properly to permit said parts to be operated simultaneously or in successive order, as the case may be, and in connection with and coacting with the parts just described the invention includes also means for carrying and feeding the carbon-paper from the rear end of the platen.

It is to be understood that the different parts of the structure herein described may be modified to a considerable extent and yet be within the spirit of my invention. For instance, means may be provided on the lever N^2 —such, for instance, as a stop or post N^3 —to engage with the table or the under face of the track-frame B or any other object to prevent the said lever N^2 from being elevated beyond a predetermined point, or the said lever can be constructed to abut against the rail of the track-frame after reaching a predetermined height, and thus be limited in its vertical movement, or an adjusting-screw N^4 may be threaded into the top of the table in the path of the rear end of the lever N^2 . Furthermore, the means for limiting the movement of the clamp P may be of form different from the pins p^3 illustrated.

The platen employed in connection with my invention is preferably of the flat-surface style, and it is to be understood that it may be hinged to the table, as at c , and be tiltable or the same be rigidly secured to the table-top and be stationary. It is to be understood also that the track-frame B may be rigid with the table, and thus be stationary, or it may be hinged at its rear end, as at b , Figs. 1 and 2, and be tiltable, and it may rest in normal position upon the upper surface of the platen and serve as an additional work-holder or be constructed of greater length.

and width than the platen and be movable independent of the platen and the platen when hinged be movable independent of the track-frame.

In the foregoing description I have disclosed a construction whereby the carbon-holders and the co-operating work holder and gage are operated by foot or manually. It is to be understood, however, that I may arrange the parts to be operated automatically and in Figs. 12 and 13 have illustrated one form of device for effecting the automatic elevation of the carbon-holders and work-clamp. In this instance the work-holders and their operating-levers are of the form already hereinbefore described; but in lieu of the connecting-link M and the foot-treadle M² for operating the parts I arrange a rearward-extending arm Q, preferably secured to or integrally formed with the rear end of the lever J² and disposed to be engaged by a stud or roller T, projecting laterally from the longitudinally-movable carriage A when the same shall have been pushed back toward the rear end of the track-frame B. As shown, the arm Q is curved and has its rear end rising up into the path of said roller T. The arrangement is such that when the said carriage impinges against the arm Q the latter will be depressed and rock the lever J² on its fulcrum to raise the said lever at its forward end and simultaneously therewith the lever N² and the work-holder P in the manner already described. It is to be understood that when the carriage is drawn forward and disengaged from the arm Q the carbon-holder-operating levers will under the action of the spring-actuated spindle L return to normal position. In this construction just described, as it will be seen, the said carbon-holders are operated automatically by the movement effected to the arm Q when the writing mechanism engages the same and rocks it.

In Figs. 2 and 3 I have shown besides the tape-work-holder I² another tape-work-holder R, supported at its rear upon a tensioning member r, arranged on the shaft i and extending forward over the platen and connecting with a member r², constructed to slide upon the clamp-holder J, and when said clamp-holder is raised to be raised also to a height above said holder, as more fully described in my pending application for patent, filed February 10, 1903, Serial No. 142,788.

Having thus described my invention, what I claim is—

1. In a type-writer, a plurality of superposed carbon-sheets, independent holders for said sheets, and means operating through said holders for elevating the carbon-sheets to different heights.

2. In a type-writer, a platen, a plurality of superposed carbon-sheets extending over said platen, holders for said sheets, and means operating through said holders for elevating each

sheet away from the platen to a special height and different from the other height.

3. In a type-writer, a platen, a plurality of carbon-sheets, independent holders for maintaining said sheets in superposed relation, and single means for elevating the carbon-holders away from the platen to position the carbon-sheets at different heights. 70

4. In a type-writer, a platen, a plurality of carbon-sheets, independent holders for maintaining said sheets in superposed relation, and means for elevating the carbon-holders successively and simultaneously away from the platen. 75

5. In a type-writer, a platen, a plurality of carbon-sheets extending over the platen, carbon-holders for each sheet independently disposed, and means for elevating the carbon-holders away from the platen to relatively different heights. 80

6. In a type-writer, a platen, a plurality of carbon-sheets an independent holder for each carbon-sheet, and a single operating means for elevating the carbon-holders away from the platen to relatively different heights. 85

7. In a type-writer, a platen, a plurality of carbon-sheets a plurality of carbon-sheet holders, and means for elevating the carbon-holders and effecting separation of the sheets. 90

8. In a type-writer, a platen, a plurality of carbon-sheets a plurality of carbon-holders, means for elevating the carbon-holders and simultaneously effecting separation of the sheets. 95

9. In a type-writer, a platen, a plurality of carbon-sheets a plurality of carbon-holders, means engaging the carbon-holders and constructed to dispose one carbon-holder in a plane different from that occupied by another carbon-holder. 100

10. In a type-writer, a platen, a plurality of carbon-sheets a plurality of carbon-holders, means for elevating the carbon-holders to different relative heights and simultaneously effecting separation of the sheets, and means for limiting the movement of said elevating means. 110

11. In a type-writer, a platen, a plurality of carbon-sheets, a plurality of carbon-holders maintaining said sheets in superposed relation, a work-holder, and means for elevating the carbon-holders to different heights and the work-holder simultaneously. 115

12. In a type-writer, a plurality of carbon-sheets, a plurality of carbon-holders maintaining said sheets in superposed relation, a combined work-holder and work-gage, and a single means for elevating the carbon-holders to different heights and also elevating the work-holder. 120

13. In a type-writer, a platen, a plurality of carbon-sheets, a plurality of carbon-holders maintaining said sheets in superposed relation, means for elevating the carbon-holders to different heights, and a work-holder 125

130

- deriving movement from the elevation of the carbon-holders.
14. In a type-writer, a platen, a plurality of carbon-holders for maintaining a plurality of carbon-sheets in superposed relation, a work-holder, and means operated by lever for effecting elevation of the carbon-holders to different heights away from the platen and also effecting elevation of the work-holder.
15. In a type-writer, a platen, a plurality of carbon-sheet holders for maintaining a plurality of carbon-sheets in superposed relation, a work-holder, means for elevating the holders to different heights away from the platen, and means for limiting movement of said holders.
16. In a type-writer, a platen, a plurality of carbon-sheet holders for maintaining a plurality of carbon-sheets in superposed relation, a work-holder, means for elevating the holders to different heights away from the platen, and means for effecting return of the holders to the platen.
17. In a type-writer, a plurality of carbon-sheet holders for maintaining a plurality of carbon-sheets in superposed relation, a work-holder, a single means for effecting elevation of the carbon-sheet holders to different heights and also moving the work-holder away from the platen, and a spring-actuated device for effecting return of the work-holders to the platen.
18. In a type-writer, a plurality of carbon-sheet holders, and means for elevating one of the carbon-holders away from the platen, the other carbon-holder being constructed to derive movement from the action of the first-mentioned carbon-holder to elevate the same away from the platen to a height different from that to which the first-mentioned carbon-holder is elevated.
19. In a type-writer, the combination with a plurality of carbon-holders, of means for effecting movement of the carbon-holders away from the platen successively.
20. In a type-writer, a plurality of carbon-holders independent of each other, a work-holder, and means constructed to elevate each of the carbon-holders and the work-holder away from the platen successively.
21. In a type-writer, a plurality of carbon-sheet holders independent of each other, a work-holder, means constructed to elevate each of the carbon-holders and the work-holder away from the platen successively, and means for limiting movement of the holders.
22. In a type-writer, a flat platen, a plurality of carbon-holders independent of each other, a work-holder, means constructed to elevate each of the carbon-holders and the work-holder away from the platen successively, and means for guiding the movement of the holders.
23. In a type-writer, a platen, carbon-rolls carrying a plurality of carbon-sheets, carbon-
- holding devices, and means for elevating the carbon-holders away from the platen to predetermined, relatively different heights.
24. In a type-writer, a plurality of carbon-rolls carrying a plurality of sheets of carbon, a plurality of carbon-holders, means for elevating the carbon-holders away from the platen, and simultaneously effecting separation of the carbon-sheets from each other.
25. In a type-writer, a flat platen, a plurality of carbon-carrying members, a plurality of work-holders, means for elevating said carbon-carrying members away from the platen and constructed to position said members in different planes.
26. In a type-writer, a flat platen, a plurality of carbon-carrying members, work-holding members, single means for moving said members to different heights away from the platen, and means for returning the same to the platen.
27. In a type-writer, a flat platen, a plurality of carbon-carrying members for maintaining a plurality of carbon-sheets in superposed relation, a plurality of work-holding members, and means for giving said members individual movement to different relative positions vertically.
28. In a type-writer, the combination of a double carbon-carrying device movable to position superposed carbons at different heights, operating means for effecting such movement of the carbon-carrying device, and a work-holding member movable with said carbon-carrying device.
29. In a type-writer, a work-holding member, a double carbon-carrying device movable to position superposed carbons at different heights, operating means for effecting such movement of the carbon-carrying device, and means for effecting movement of the work-holding member with the double carbon-carrying device.
30. In a type-writer, a flat platen, a combined work holding and guiding member, a plurality of carbon-carrying members movable to position superposed carbons at different heights above the platen, operating means for effecting such movement of the carbon-carrying members, said means operating also to effect movement of the work holding and guiding member away from the platen.
31. In a type-writer, a plurality of carbon-rolls, a plurality of carbon-sheets carried thereby, a plurality of carbon-holding members, means for elevating the carbon-sheets to relatively different heights away from the platen, and means for maintaining the carbon-sheets taut.
32. In a type-writer, a flat platen, a plurality of carbon-sheet holders movable to position superposed carbons at different heights above the platen, and an independent work-holding tape disposed on the platen.

33. In a type-writer, a flat platen, a plurality of carbon-holding members, independently-pivoted but coöperatively-connected levers connecting with the carbon-holders, and an operating device connecting with one of said levers for effecting elevation thereof.

34. In a type-writer, a flat platen, a plurality of carbon-holders, independently-pivoted but coöperatively-connected levers connected to said carbon-holders, and a treadle device constructed to actuate said carbon-holder levers.

35. In a type-writer, a plurality of carbon-holding members, a lever connecting with one of said holding members, a treadle device constructed to elevate said lever, an independent lever connecting with the other of said carbon-holding members, and means for connecting said levers and constructed to effect coöperation thereof to elevate the same to relatively different heights.

36. In a type-writer, a plurality of carbon-holding members, levers connecting with said members and independent of each other, means connecting said levers and constructed to effect successive movement thereof, and means for actuating said levers.

37. In a type-writer, a plurality of carbon-holding members, a plurality of levers connecting with said members in juxtaposition one with the other, means for operating one of said levers, means connecting said levers and constructed to effect coöperation therewith to position one carbon-holding member at a height relatively different from that to which the other is actuated.

38. In a type-writer, a plurality of carbon-holding members, a plurality of operating levers connecting therewith, a device for ac-

tuating one of the levers, means carried by one of the levers and engaging the other lever and constructed to effect successive movement of said levers when actuated.

39. In a type-writer, a plurality of carbon-holding members, a plurality of operating levers connecting therewith, a work-holding member, and means connecting the carbon-holding members and the work-holding member and constructed to effect successive movement of the respective members.

40. In a type-writer, a plurality of carbon-holding members, a plurality of operating levers connecting therewith, a work-holding member, means connecting the carbon-holding and work-holding members and constructed to effect successive movement thereof, and means for limiting the extent of movement of said members.

41. In a type-writer, the combination with a platen, of a plurality of carbon-holders disposed contiguous to said platen, a plurality of independent operating-levers connected with the said members, an independent work-holding member disposed contiguous to said operating-levers, means for actuating said operating-levers, means connecting said levers and said work-holding member and constructed to effect actuation of said carbon-holders and work-holder, and a spring-actuated device for effecting return of said members to normal position.

In testimony whereof I affix my signature in the presence of two subscribing witnesses.

GEORGE W. DONNING.
